SIGNAL-OPERATED INDICATING DEVICE

Heinz Hofmann, Berlin, Germany; vested in the
Alien Property CustodianApplication February 18, 1939, Serial No. 257,153
In Germany February 18, 1938

5 Claims. (Cl. 250—11)

The invention relates to the operation of electric indicating devices, such as glow discharge lamps, telephones or the like by signal voltages, such, for instance, as voltages arriving from marker beacon radio transmitters in order to enable the pilot of an aircraft or other vehicle to ascertain in well known manner the position of the craft with respect to the beacon.

The invention consists in certain features of novelty which will appear from the following description and be particularly pointed out in the appended claims, reference being had to the accompanying drawing in which:

Fig. 1 shows the circuit arrangement of one embodiment of the invention, while Fig. 2 represents the circuit arrangement of an improvement upon this embodiment.

In certain types of aircraft locating systems, radio marker beams are located at predetermined geographical points and when the aircraft is passing such a point or is travelling on a line directed towards such point, a visual signal and an audible signal are produced to indicate to the pilot the geographical location of the aircraft. Such known systems require grid-controlled amplifier tubes in connection with the radio receiving equipment on the aircraft, one or more of the amplifier tubes operating at a predetermined point on the amplification characteristic curve. However, it is quite apparent that the aircraft may pass such a marker at a high level or at a low level and the intensity of the signal received on the radio receiver may vary between very wide limits. It is possible with such systems that the amplification power of one or more of the grid-controlled amplifier tubes in the aircraft receiver will vary depending upon the field intensity of the marker signal at the point where it is to be determined, thus if the aircraft should pass over a radio marker at a low height, the field intensity may be many times greater than where the aircraft passes over the same marker at a greater height. Furthermore, the same disadvantage may arise if successive markers unintentionally produce different field intensities at a given height. One of the disadvantages of such an arrangement is particularly apparent where two separate signal indicators, for example a visual signal (produced by a glow discharge lamp or the like) and an audible signal (produced by a telephone receiver or the like) are provided on the aircraft. This disadvantage is then manifested as an apparent time spacing of the two signals and even though this spacing may be comparatively slight, it may give rise to confusion in the mind of the pilot as to which signal to follow. In accordance with the present invention, two kinds of signal indicator devices are used on the aircraft, for example a telephone and one or more glow lamps. However, one of the amplifier tubes which feeds these two classes of signal devices is

so designed that normally (i. e. when no marker signals are being received) the tube is biased substantially entirely to plate current cutoff or at least to the lower region of the amplification curve having very little slope. However, upon the receipt of a marker signal, the signal acts to shift the working point of the tube to the upper region of steep slope, thus enabling maximum plate current to be utilized for controlling both indicators regardless of the field intensity of the received marker signal. Within certain limits therefore, the response of the telephone and the glow lamps are substantially instantaneous and independent of the actual field strength of the marker signal at the point where the aircraft passes. This follows from the fact that the amplification power of the tube is shifted even for very low signal strengths and finally it approaches maximum plate current. Since the telephone device is essentially a power operated device, whereas the glow discharge lamps are essentially voltage responsive devices, the maximum power output of the tube is effective substantially simultaneously on both devices, thus producing substantially simultaneous indications independently of field strength. Accordingly, the present invention produces two fundamental advantages when applied to radio marker systems for aircraft and the like as follows:

- 30 1. The indicating device whether aural or visual, is operated instantaneously because the amplifier tube is substantially completely blocked until the controlling device becomes effective.
- 35 2. From a definite initial value the system operates independently of amplitudes since the controlling effect will cause the amplifier tube to increase gradually to the maximum anode current. This advantage is of considerable importance since the maximum anode current is always available for operating the indicating device substantially independent of the magnitude of input signal voltage.

In the arrangement according to Fig. 1 the low frequency signal voltages taken from the output circuit of a receiver are conveyed over a transformer 1 to an electron tube 2. Tube 2 while illustrated as of the well-known pentode type comprising a cathode 2a, a control grid 2b, a shield grid 2c, a suppressor grid 2d, and a plate 2e, may be of any other well-known type. The heater filament for the cathode 2a is indicated by the numeral 2f. In accordance with well-known practice, the suppressor grid 2d may be connected directly to the cathode 2a by the wire 2g. The by-pass condensers 2h, 2i, are provided across the various resistances for the well-known purpose of preventing singing in the amplifier. On the other hand, the condenser 1 is a coupling con-

denser of sufficient capacity to allow a portion of the amplified signal waves to be applied to the rectifier network which includes one-way rectifier 8, resistance 9 and the resistance 10. The resistance 3 being connected in the plate-to-cathode circuit of tube 2 imparts a negative bias to the control grid 2b even for extremely small values of plate current. The value of this normal plate current can also be controlled in the well-known manner by adjusting the potential of the plate 2e and the screen grid 2c by means of the respective resistances 4, 5 and 6. The screen grid 2c is connected between the voltage dividing resistors 4 and 5. Resistances 3, 4, 5, 6 are proportioned in the well-known manner so to adjust the working point of tube 2 that this tube is almost completely blocked in its state of rest. However upon receipt of signal waves, a small proportion of the signal voltage flows through the tube 2 and is conveyed from the anode circuit over a condenser 7, in order to be rectified by a rectifier 8. The continuous or unidirectional voltage arising at resistances 9, 10 serves as control grid voltage for tube 2 and in accordance with the invention acts to displace the working point thereof into the region of steep slope. Consequently the maximum plate current will be produced in the output circuit of tube 2 substantially regardless of the amplitude of the input signal waves to grid 2b and therefore the response of the tube 2 will be substantially independent of the field intensity of the radio marker wave. As a result of the rectifier 8 being conductive in the manner indicated by the drawing, that is in the direction of the arrow, when a marker signal is impressed upon grid 2b a portion of the amplified signal flows through the rectifier 8 in such a direction that it develops across the resistance 3 a voltage drop which is of opposite polarity to the normal negative blocking bias produced by said resistor 3. In the drawing, the normal bias across resistor 3 is indicated by the full line designations + and - whereas the bias resulting from the action of the one-way rectifier 8 is indicated by the dotted signs + and -. Included in the anode circuit are the indicating means, such, for example, as glow lamps 11, 12 and a telephone 14 coupled to the anode circuit by a transformer 13. As soon as the described regulating arrangement and hence the increase of the power amplification ratio of the tube 2 become effective the indicating means 11, 12, 14 will be actuated abruptly. Accordingly, an intensified signal indication is produced so that even weak signals will produce a desired minimum signal strength.

The arrangement according to Fig. 2 is different in operation from the arrangement represented in Fig. 1 inasmuch as different signal voltages, namely, two different frequencies are conveyed to tube 2, each of which has to actuate an indicating device allotted to it. This arrangement may be used, for instance, if a vehicle, such as an aeroplane, has to receive the radiation of two marking transmitters one of which is modulated with the frequency f_1 while the other is modulated with the frequency f_2 . For this purpose oscillatory circuits 15, 16 are arranged in the anode circuit, one of which is tuned to the signal frequency f_1 while the other is tuned to the signal frequency f_2 . To each of these circuits an indicating device is coupled, such as a glow lamp 17 or 18, respectively. For instance, glow lamp 17 is to be operated only by the frequency f_1 while the glow lamp 18 is only to respond to frequency f_2 . For each of these indicating circuits, 75

which are separated from each other by the resonant circuits, a voltage is derived over resistances 19, 20 or condensers 21, 22. These voltages are rectified by rectifiers 23, 24 and are employed for affecting the power amplification ratio of the tube in the manner before stated. In order also to provide for an aural indication, a telephone 25 is included in the anode circuit.

What is claimed is:

1. In an arrangement for producing substantially simultaneously two different kinds of signals on an aircraft or the like under control of a received radio marker signal, comprising a visual indicator of the type which requires a predetermined minimum voltage level before producing an indication, an aural indicator of the type which produces an indication for substantially all levels of voltage applied thereto, each adapted to be controlled by low frequency signals received on the aircraft from said radio marker, an amplifier tube for amplifying said low frequency signals, said amplifier tube being normally statically biased so that the tube is substantially entirely blocked, and means including an auxiliary biasing circuit responsive to the receipt of a marker signal of any intensity sufficient to produce an indication by said aural indicator to reduce the said blocking bias and thereby to increase steeply the amplification power of said amplifier tube to produce an indicator control current which is substantially independent of the field intensity of said radio marker at the point where the indications are given, so long as said intensity is sufficient to produce a response by said aural indicator.
2. An arrangement according to claim 1 in which the aural signal indicator is of the telephone type and the visual signal indicator of the glow lamp type.
3. An arrangement according to claim 1 in which the indications of the aural and visual signal indicators are produced substantially simultaneously independently of the field strength of the radio marker.
4. An arrangement according to claim 1 in which the visual indicator comprises a pair of glow lamps each of which is coupled to the plate circuit of said amplifier tube through an individual selective filter whereby said glow lamps respond to their individual signals to produce substantially simultaneous indications.
5. In an arrangement for producing simultaneously two different kinds of signals on an aircraft or the like under control of a received radio marker signal, comprising two indicators one of which responds in proportion to the intensity of the signal from the weakest to the strongest, the other of which requires a minimum impressed signal level before it responds, an amplifier tube of the control-grid type for amplifying said signals, said amplifier tube having its control grid normally statically biased so that the tube is substantially entirely blocked, means including an auxiliary biasing resistor effective on any received marker signal which is of sufficient strength to produce a response in said one of said indicators to simultaneously reduce said blocking bias and thereby to increase sharply the amplification power of the amplifier to insure that said other indicator produces a simultaneous response whereby the production of the two types of indications is simultaneous even for very weak field intensities of the radio marker at the point where the indications are given.
